UNITED STATES PATENT OFFICE

2,646,062

AUTOMATIC WELL FLOW VALVE

Jeddy D. Nixon, New Braunfels, Tex., assignor of
one-half to Wilson Supply Company, Houston,
Tex., a corporation of Texas

Application November 8, 1948, Serial No. 58,995

9 Claims. (Cl. 137—155)

1

This invention relates to new and useful improvements in automatic well flow valves.

One object of the invention is to provide an improved automatic flow valve adapted to be mounted on the outside of an eduction tubing for supplying pressure fluid from the outer casing.

Another object of the invention is to provide an improved automatic flow valve employing a movable weight member for opening and closing the valve, whereby the weight provides the pressure differential between the pressure fluid and the hydrostatic pressure of the liquid in the tubing, necessary to operate the valve.

A further object of the invention is to provide an improved automatic valve wherein the flow passages are relatively large so as to provide free flowing which substantially eliminates sanding up and cutting; and also whereby a low pressure differential operates the valve and large volumes of pressure fluid are supplied under high velocity with little or no seat cutting.

Still another object of the invention is to provide an improved automatic flow valve of the type described employing an elastic valve seating member which not only provides cushioned closing but withstands severe pounding and will not leak.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is an elevation of an automatic valve constructed in accordance with the invention mounted on an eduction tubing in an outer casing.

Fig. 2 is an enlarged view of the upper half portion of a string of tubing and casing having the upper portion of one of the valves mounted therein, a portion of the sub and the upper portion of said valve being illustrated in section with the valve closed.

Fig. 3 is a vertical sectional view of the lower portion of the sub and valve.

Fig. 4 is a vertical sectional view of the upper portion of the valve assembly in its closed position.

Fig. 5 is a similar view of the upper portion of the valve assembly in its open position.

Figs. 6 and 7 are horizontal cross-sectional views taken on their respective lines of Fig. 2, and

Fig. 8 is a similar view taken on the line 8—8 of Fig. 3.

2

In the drawings the numeral 10 designates a short length of tubing or sub which is preferably of the upset collar type and is formed with pins 11 at each end having annular beveled shoulders 12 at their bases. The pins receive the usual coupling collars 13, whereby the sub may be connected in a string of well tubing. An upper hanger 14 is mounted on the side of the sub adjacent the upper shoulder 12, while a lower hanger 15 is mounted under the upper hanger adjacent the lower shoulder. These hangers may be welded in the sub.

The upper hanger 14 has a vertical bore 16 open at the bottom of said hanger and closed at its top. A lateral duct 17 leads from the upper end of the bore to a port 18 in the sidewall of the sub. A bushing 19 is countersunk in an annular recess or socket 20, surrounding the bore 16. The bushing is sealed off from the bore by a gasket 21 and has a tubular shank 22 fitting snugly in said bore. The upper end of the shank terminates below the duct 17 and is formed with an annular valve seat 23 which receives a check valve ball 24. A cylindrical, perforated cage or sleeve 25 extends between the upper and lower hangers 14 and 15, the upper end of the cage fitting snugly around a dependent boss 26 on the bottom of the bushing and being removably inserted in the counterbore 20.

A tubular pedestal 27 carries external screw threads 28 and is received in a vertical screw-threaded bore 29 extending through the lower hanger 15. The pedestal is fastened in place by a set screw 30. A head 31 is formed on the upper end of the pedestal and has an upstanding annular boss 32 which telescopes the lower end of the cage 25, whereby the latter is seated on the pedestal. It will be seen that by loosening the set screw 30, the pedestal, by unscrewing, may be lowered sufficiently to withdraw the upper end of the cage from the socket 20 of the upper hanger, whereby the cage may be lifted off of the head 31, when it is desired to gain access to parts in the cage or for any other purpose.

An elongate, cylindrical weight bar 33 is movable vertically in the cage, being of less diameter and spaced from the inner wall of said cage. The bar has a depending guide stem 34 engaging in the bore 35 of the pedestal. At its upper end, the bar has a socket 36 receiving the depending lug 37 of a valve head 38 which is pivoted therein on a transverse pin 39. The valve head has a screw-threaded axial bore 40 receiving the lower screw-threaded end of a valve stem 41, fastened therein by a set screw 42. An elastic valve

collar 43, formed of soft plastic or other elastic material, is countersunk in the top of the head 38 within the upper end of the cage 25. The upper side of the collar has an inclined annular face 44 adapted to engage a complementary seat 45 at the lower end of the bore 46 of the bushing 19, thereby sealing off said bore and shutting off flow of fluid through said bore to the bore 16, duct 17 and port 18. The bores 46 and 16, the duct 17, and port 18, form a flow passage between the sub 10 and the cage 25.

An annular flow restricting member 47 is formed around the medial portion of the stem 41 so as to have a free sliding fit in the lower end of the bore 46, when the collar 43 is seated. The member 47 has an inclined, annular shoulder 48 at its top. A pair of spaced flanges or collars 49 surround the upper end portion of the valve stem, one of said flanges being flush with the upper end of said stem and thus providing a flat surface for receiving the check ball 24 and holding it out of its seat 23, when the valve is closed. These flanges are slightly less in diameter than the bore 46 of the bushing so as to provide a restricted flow space therearound.

It will be noted (Figs. 3 and 4) that when the weight bar 33 is seated on the pedestal head 31, the valve collar 43 will be unseated and the member 47 will be withdrawn from the bore 46. However, the flanges 49 will remain in said bore, thus restricting the flow of pressure fluid from the cage 25 to the port 18. The pedestal head 31 has a plurality of vertical ducts 50 so that the pressure fluid may flow therethrough. When the weight bar 33 is elevated and the collar 43 of its valve head 38 is seated, the bottom of said bar will offer a greater cross sectional area to the pressure fluid and the bar will thus be held in its elevated position.

The sub 10 is connected in a string of oil education tubing 51 which is mounted in a string of casing 52 in accordance with common oil-field practice, as is shown in Fig. 1. The automatic valve, indicated generally by the numeral 53 in Fig. 1 is disposed in the casing which is filled with a suitable pressure fluid, such as gas under a working pressure of 400 to 500 pounds per square inch. When the valve is closed, as shown in Figs. 2 and 4, the check valve 24 is unseated, but the flow passage to the port 18 is shut off because the valve collar 43 is seated and thus pressure fluid cannot enter the tubing. When the valve is opened, as shown in Fig. 5, and gas is not flowing through the valve passage to the port 18, the valve ball 24 will be seated and thus liquid or oil cannot flow from the tubing through said port into the casing.

The weight of the bar 33 constitutes a differential equivalent to a pressure differential between the pressure of the gas in the casing and the hydrostatic pressure of the liquid in the tubing above the port 18. As an illustration, if the gas in the casing is exerting a pressure of 460 pounds per square inch against the bottom of the bar 33, said bar may weigh substantially 19 lbs. and thus the valve will remain closed until the hydrostatic pressure in the tubing above the port 18, reaches substantially 440 pounds per square inch, whereupon the weight bar will fall, thus unseating the valve collar 43 and withdrawing the pilot valve 47 from the bore 46.

The instant the pilot valve body 47 leaves the lower end of the bore 46, the flow annulus will be increased because of the inclined shoulder 48 and this will cause the valve to open with a snap action. When the valve is opened to flow position

as is shown in Fig. 5, the pressure fluid will bypass the flanges 49, unseat the ball 24 and flow into the sub 10 and tubing 51, by way of the port 18. This flow will continue until the slug of oil is elevated in the tubing in the usual way.

It will be observed that the flow past the flanges 49 will be restricted and its velocity thus increased. This velocity will pick up as the slug of oil is elevated in the tubing because the load will be lightened. The stem 41 and the flanges 49 act as pistons and when the back pressure acting downwardly on this piston decreases to a predetermined point, the pressure fluid will pick up the piston and close the valve. Where the opening pressure differential is substantially 20 pounds per square inch, the closing pressure differential will be approximately 80 pounds per square inch. This difference in pressure differentials is due to the energy required to lift the weight bar.

When the weight bar is lifted, the inclined shoulder gradually decreases the flow space as it enters the bottom of the bore 46, until the point is reached where the valve is closed with a snap action. It is believed the operation of the valve under starting or kickoff conditions will be understood without further explanation. Like all automatic valves, this valve will remain closed until the liquid in the tubing rises sufficiently to build up the required hydrostatic pressure to open it.

The valve herein set forth has many advantages. It is pointed out that all flow openings such as 18, 17, 16 and 46 are large, particularly when compared to the small or pin-point openings found in the usual automatic valve. While the annular flow space around the flanges 49 is restricted it is ample to prevent clogging or sanding up and the consequent cutting.

As a rule, the flow passages of automatic valves are so small that it is necessary to have these valves open at relatively high pressure differentials of from 100 to 200 pounds per square inch in order to flow into the tubing enough cubic feet of gas under enough pressure to elevate the slug of oil. In the valve herein set forth, the inlet flow passages being large and the valve opening on a low differential, large volumes of gas or pressure fluid under high velocity are admitted. This greatly reduces seat cutting and the volume of gas admitted to the tubing is depended upon rather than the high pressure of such gas.

By use of the elastic collar 43, which is preferably made of a medium hard plastic, such as "Micarta," a cushion seating is had and the valve, when closed, will not leak and will stand considerable pounding. While the collar is relatively soft, it is not soft enough to permit grains of sand to embed therein.

The valve which has been described herein, is known as a tubing type, because the oil or liquid is elevated in the tubing and the pressure fluid is exteriorly supplied, and is to be distinguished from casing type valves wherein the pressure fluid is supplied from the tubing and the liquid elevated in the casing. This application is in some respects related to my copending application, Serial No. 58,996, filed of even date herewith.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. An automatic well flow valve including, an upper support adapted to be mounted on a tubular conductor having a port, a lower support adapted to be mounted on a tubular conductor, the upper support having a valve seat and a flow passage from said seat adapted to be connected to the conductor port, a pedestal carried by the lower support, a perforated cage mounted on the pedestal engaging the upper support, a movable weight bar in said pedestal, and a valve on the upper end of the bar adapted to engage the seat. 10

2. An automatic valve as set forth in claim 1, and a stem extending from the valve into the passage of the upper support, and flow restricting means on the stem in said passage. 15

3. An automatic valve as set forth in claim 2, and a flow restrictor on the stem adapted to enter the passage through the seat. 20

4. An automatic well flow valve including, a support adapted to be mounted on a tubular conductor having a port, a passage in said support adapted to be connected to said port, a bushing mounted in said support having a bore connected with the passage at its upper end, a valve seat at the lower end of said bushing bore, a weight bar, a valve head mounted on the upper end of said bar, an upstanding valve stem 30 in said head, an elastic collar on said head adapted to engage said seat and surrounding said stem, a flow restrictor on said stem above the collar adapted to engage in said bushing bore, and flow restricting flanges on said stem in said bushing bore. 35

5. An automatic valve as set forth in claim 4, wherein the bushing has a valve seat at the upper end of its bore, and a check valve in the support passage adapted to engage said last named seat. 40

6. An automatic flow valve including, a sup-

port adapted to be mounted on a tubular conductor having a port, said support having a right angular flow passage therethrough adapted to be connected with said conductor port at its upper outer end, a bushing inserted in the flow passage having a valve seat at its bottom, a weight bar, a valve means at one end of the weight bar having a member slideable in the bushing, and flow restricting means carried on the member in the bushing for raising the bar to seat the valve means. 5

7. An automatic well flow valve as set forth in claim 6, wherein the bushing has an additional valve seat at its upper end, and a check valve in the flow passage disposed to engage said seat for shutting off a reverse flow through said passage. 10

8. An automatic well flow valve as set forth in claim 6, with a support below the lower end of the weight bar, and a removable foraminous cage carried by the last named support and loosely surrounding the weight bar. 20

9. An automatic well flow valve as set forth in claim 6, wherein the valve means includes an elastic collar for engaging the valve seat. 25
